2 Claims

ABSTRACT OF THE DISCLOSURE

A railroad car with one or more roof hatches extending over the length of the car has an air motor connected to each hatch cover for normally holding a hatch cover closed, and a movable bar or lever on the roof extending beyond the sides of the car to engage a trackside rail, whereby the bar moves to operate a valve to cause the motor to open the hatch cover and hold it open only while the bar engages the trackside rail.

BACKGROUND OF THE INVENTION

Railroad cars of some types, such as covered hopper cars, have openings or hatches through which they are loaded. The hatches are provided with covers, the opening and closing of which may require a considerable amount of work and time. Means for automatically opening and closing hatch covers are shown in Patent 3,251,487 to P. F. Giesking. The present invention has many important advantages over prior apparatus. First, it is capable of opening very large hatches, without possible damage to the cover or trackside rail. The danger of an accidentally open hatch cover is practically obviated. The hatch cover is held closed by a powered motor, and if a hatch cover is opened accidentally or manually, it is closed automatically and immediately by the motor. These features are important because an open hatch cover may be dangerous to the lading and also to personnel and the car itself. From an operational standpoint, automatic opening and closing of continuous hatch covers permit a train of cars to be loaded while they move slowly past a chute or loading point.

SUMMARY OF THE INVENTION

The invention relates to a hatch cover or covers for a closed railroad car and particularly to mechanism for opening and closing a hatch cover automatically. The mechanism includes a compressed air motor, in the form of a cylinder and a piston connected to the cover, and controlled by a valve to keep the cover closed. A pivoted or shiftable bar is mounted on the roof of the car and extends beyond the sides of the car to engage a trackside rail which causes the bar to turn or slide and thereby move a valve operator. The valve, then, is operated to actuate the motor to its opposite position and thus open the hatch cover. The valve and motor remain in their operated position as long as the bar engages the trackside rail, and thereafter the valve and motor shift back to their normal positions, closing the hatch cover and positively holding it closed. The valve may control a plurality of motors for operating a plurality of covers.

BRIEF DESCRIPTION OF THE DRAWING

The invention is illustrated in the accompanying drawing, of which:

FIG. 1 is a schematic showing three railway cars in plan with a rub rail to actuate the center car by contact with a roller on the actuating lever carried on the car.

FIG. 2 is an enlarged top plan of one car showing a

2

single hatch cover, the cylinder and actuating mechanism in plan.

FIG. 3 is an enlarged fragment of FIG. 2 showing the actuating mechanism.

FIG. 4 is a section taken generally along line 4—4 of FIG. 3.

FIG. 5 is an enlarged section of the cylinder to open the hatch cover with the hatch cover in closed position.

FIG. 6 is a section similar to FIG. 5 with the hatch cover in open position.

FIG. 7 is a partial side elevation of the means for mounting the hatch cover for pivotal movement.

FIG. 8 is a schematic of an air system.

FIG. 9 is a top plan of another embodiment of the invention.

FIG. 10 is a side elevation of the embodiment shown in FIG. 9.

DESCRIPTION OF THE PREFERRED EMBODIMENTS

FIG. 1 shows three cars 10, 11, 12 of a train, the first two cars having a single continuous hatch 14, which is closed in car 10, and has an open cover 16 in car 11. Car 12 has two elongated hatches with suitable covers 18, 20. The covers are shown connected by a plurality of straps 22 or 24 to torque tubes 26 or 28. Each car has a valve actuating assembly 30 on the roof thereof, which is shown in simplified schematic form in FIGURE 1. The actuating assembly 30 extends beyond the sides of the car to engage a trackside rail 32 which may be about as long as two or more cars and is located at the loading site. It may be assumed that the loading point is near the midpoint of rail 32. It is evident that other arrangements of trackside rails and actuating assemblies may be used.

Referring particularly to FIGURES 3 and 4, the hatch 14 is in the middle of a curved roof 40. Actuating assembly 30 includes bars 41 and 42 connected by plates 43, 44 to a center bar 46. The latter is fastened to a U-shaped bar 48 connected by tensioned springs 49, 50 to brackets 51, 52 on the roof. The roof 40 has pockets 53, 54 into which bars 41 and 42 partly extend, and the outer ends of these bars are provided with rollers 55, 56 for engaging the trackside rail 32. Brackets 57, 58 are welded to plates 59, 60 and pivotally support links 61, 62, which at their other end are pivotally connected to bars 41 and 42. Link 62 is connected to a double sided cam 64 having a camming surface 66 engaging a roller 68 on an operator of a valve 70. Additional supporting brackets 72, 74 are provided for links 61, 62 and for cam 64 and plate 76.

Hatch cover 16 may have any suitable construction, as indicated in FIGURES 1, 2, 5 and 6. It may be supported by bearings for torque tube 26 disposed therealong, as required. A spur gear 80 is fixed to tube 26 and is coupled to a gear sector 82 in a housing 84. Gear 82 is pivoted on shaft 86 and has an arm 88 pivotally connected to piston rod 90 of air motor 92. The latter is itself pivotally mounted on bracket 94, so that moving piston rod 90 opens and closes the hatch.

The pneumatic circuit of the motor is shown in FIGURE 8. The train line 100 supplies compressed air through globe valve 102 to a suitable reservoir 104. The reservoir is connected to the input of four-way valve 70. The valve has an exhaust port and two ports connected on opposite sides of piston 106 to cylinder portions marked CYL. 1 and CYL. 2. Valve 70 is spring loaded and is arranged so that air pressure is maintained on the side of the cylinder which keeps the hatch cover in a closed position, while the other side of the motor cylinder is connected to the valve exhaust port, and thus vented to the atmosphere.

FIGURES 9 and 10 shows an alternative valve actuator comprising a lever 110 having a fulcrum at 112 and spring wipers 113, 114. Lever 110 is anchored to the car by return spring 116 and is provided with guides 117, 118 and stops 119, 120. Valve 122, similar to valve 70, is positioned to be operated by lever 110 when one of the wipers 113 or 114 engages rub rail 32 and causes lever 110 to turn. Valve 122, which is spring loaded then controls motor 92, as previously described in connection with FIGURE 8. It is evident that valve 122, like valve 70, may also be operated manually, as may be desired for inspection or other purposes.

From the above description and the drawings, it will be obvious to those skilled in the art that the apparatus operates to open and close a hatch automatically for continuous loading. Normally the spring biased valve maintains pressure in the side of the motor cylinder which holds the piston 106 in the position which keeps the hatch closed. When a car reaches the loading site, trackside rail 32 moves valve actuator 30 or 110 and causes air valve 70 or 122 to reverse motor 92 and open the hatch cover. As the air valve is spring loaded, pressure must be maintained on the valve actuator 30 or lever 110 to keep the hatch open. Hence, when the rub rail 32 is passed the hatch is closed. Accidental bumping of the valve operating mechanism will not cause the hatch to open. Four way air valves are well known and a suitable example is Rivett Model 2310 made by the Rivett Lathe & Grinder, Inc. of Boston, Mass. It will be evident that proper operation will still be obtained if one or more of cars is turned around. If the car has several hatch covers, as does car 12 in FIG. 1, the several motors are connected identically in parallel to air valve 70 in FIG. 8.

Since variations and modifications of the disclosed em-

bodiments are within the purview of the invention, the disclosure should only be considered illustrative of the invention, the scope of which is defined in the following claims.

5 What is claimed is:

1. A railroad car having a body and a roof thereon and a hinged hatch cover on said roof; a motor on said car, including an air cylinder connected to said hatch cover for opening and closing said cover; valve means for said air cylinder mounted on said car for normally causing said motor to urge said hatch cover to its closed position; valve control means, including a movable actuating member extending transversely beyond the perimeter of the body of the car on both sides thereof; and a stationary trackside rail for engaging said actuating member for actuating said valve means to operate said motor to open said cover and hold it open only while the actuating member engages said rail.

2. The apparatus of claim 1, including a plurality of like hatch covers; a motor for each hatch cover connected to said valve means for opening or closing all said hatch covers together.
